BUILDING COLUMN

John Stanley Donahue, Brookline, Mass., and
George E. Strehau, Leonia, N. J.; said Strehau
assignor to said Donahue

Application April 18, 1945, Serial No. 588,954

4 Claims. (Cl. 189—42)

1

This invention relates to reinforced structural columns of the cylindrical, concrete-filled type commonly used in building construction, and pertains more particularly to improvements in bracketed columns having beam-supporting wings or plates welded thereto.

The principal purpose of the invention is to provide a column having a bracket plate secured thereto in such a manner that it is capable of adequately withstanding the three types of stresses to which the column and bracket are normally subjected, namely: rotational stress upon the plate caused by the floor-supporting beam attached thereto; compressional stress upon bracket; and lateral bulging or bursting stress upon the column casing, caused by the vertical pressures of beams or cap plates on the concrete core.

Recommended embodiments of the invention are shown in the accompanying drawings, but it will be understood that the structural details of the devices herein illustrated and described may be varied to suit particular conditions without departing from the essence of this invention as defined in the appended claims. In the drawings,

Fig. 1 is a fragmentary elevation of a column having a bracket plate secured thereto in accordance with one form of the invention, the column casing being broken away and the concrete filling being omitted;

Fig. 2 is a section on line 2—2 of Fig. 1;

Fig. 3 is a view similar to Fig. 1, showing a modified form of bracket connection and beam support;

Figs. 4 and 5 are sections on lines 4—4 and 5—5, respectively, of Fig. 3;

Fig. 6 is a view similar to Fig. 1 showing another modified form of bracket connection;

Fig. 7 is a section on line 7—7 of Fig. 6;

Fig. 8 is a side view of a column provided with a further modified form of bracket; and

Fig. 9 is a section on line 9—9 of Fig. 8.

In each of the figures, the beam connecting bracket comprises a compression plate having curved arms welded to the exterior of the column casing and equipped, if desired, with laterally projecting flanges to which a beam-supporting plate or the beam itself may be bolted or otherwise fastened, or on which the beam end may rest; and in each figure, the type of beam for which the respective brackets are adapted is shown in broken lines. It will be understood, however, that a compression plate consisting of a single arcuate member, with or without attached lateral flanges between its curved arms, will suf-

2

fice for certain installations; for the beam-supporting plate may be welded directly to the compression plate if the projecting flanges are omitted.

In the embodiment illustrated in Figs. 1 and 2, the tubular column casing 11, which is normally filled with concrete or other plastic core material, has a vertical slot to receive the inner margin or web 12 of a bracket plate 13, the top of the plate having a notch 14 defining a lug or tension toe 15 which is hooked behind the casing wall when the web 12 is inserted in the casing slot by an upward rotational movement. The plate 13 has an extension or compression heel 16, depending below the casing slot and bearing against compression plates having curved arms 17 to which the heel 16 is bolted, welded or otherwise rigidly fastened. The web 12 is preferably welded in the casing slot, as described in Lally Patents 2,143,219 and 1,537,833.

In the arrangement shown, the extension heel is secured and braced between a pair of laterally projecting flanges or lugs 18 integral with the respective arms 17 which conform to the curvature of the casing. The heel 16 is secured to said flanges by bolts 19 or other fastening means. The arms 17 of the duplex compression plates are welded to the casing, as indicated at 20.

The outwardly projecting portion of the bracket plate may have openings 21 to receive bolts which attach the beam 22 thereto, as usual; and a column bracket of the character described will afford adequate support for the beam and the weight carried thereby. Rotational stress upon the projecting plate is resisted by the tension toe 15, compressional stress is borne by the heel 16, and bursting stress is restrained by the arms 17 which also assist in offsetting rotational and compressional stresses and thus serve as a compensating medium upon which the different stresses react in opposite directions.

In the modified embodiment of Figs. 3 to 5, the plain bracket plate 23 is inserted in a slot of the casing 24 to which it is welded; and the beam 25 attached thereto, is additionally supported by curved arms 26 welded to the exterior of the column and having their lateral flanges 27 welded together and provided with cap plates 28, integral therewith or attached thereto, on which the bottom of the beam end 25 is seated.

In Figs. 6 and 7, the bracket plate 29 is inserted in and welded to the casing 30, substantially as shown in Figs. 3 to 5; and the curved arms 31 have their lateral flanges 32 welded to the oppo-

site sides of the plate in the central region thereof.

In the further modification of Figs. 8 and 9, the lateral flanges 32 of the curved arms 33 constitute the bracket plates between which the web of beams 34 is directly bolted, the curved arms 33 of the duplex compression plate being welded to the exterior of the casing as aforesaid. Although this bracket construction is less effective than those previously described, it affords adequate support for beams carrying relatively light loads.

The bracketed building columns herein disclosed, and more particularly the construction shown in Figs. 1 and 2, afford a simple, practical and economical means for securely supporting heavy beam loads and effectively resisting the various stresses which tend to distort the column casing or displace the bracket plates mounted thereon. The curved arms of the compression plates which constitute an important feature of this invention, extend a substantial distance around the column casing, involving not less than ninety degrees of the column circumference; and it will be understood, as aforesaid, that a unitary compression plate having one or more laterally projecting flanges and integral curved arms extending therefrom in both directions, may feasibly be employed in some cases, in place of the pair of duplex compression plates herein illustrated.

We claim:

1. In a cylindrical building column, a bracket comprising a beam-supporting plate, and a pair of compression plates each having a curved arm fitting the exterior of the column and welded thereto, said compression plates having laterally projecting flanges disposed on opposite sides of said beam-supporting plate and fastened thereto, the column having a metal casing provided with a vertical slot, and the beam-supporting plate having a web inserted into the column through said slot and welded therein.
2. In a cylindrical building column, a bracket comprising a beam-supporting plate, and a pair of compression plates each having a curved arm fitting the exterior of the column and welded thereto, said compression plates having laterally projecting flanges disposed on opposite sides of said beam-supporting plate and fastened thereto, the column having a metal casing provided with a vertical slot, and the beam-support-

ing plate having a web inserted into the column through said slot and welded therein, the upper edge of said web having a notch receiving a portion of said casing and an interior tension toe, and the bottom of said beam-supporting plate having an extension depending below said slot and bearing against the exterior of the casing to provide a compression heel, said flanges being fastened to said heel.

3. In a building column having a tubular metal casing formed with a vertical slot, a beam-supporting bracket comprising a plate adapted to be attached to the beam, the plate having a web inserted into the column through said slot and welded therein, the upper edge of the plate having a notch receiving a portion of the casing and a tension toe bearing against the interior of said casing portion, the bottom of the plate having an extension depending below said slot to provide a compression heel, and a compression plate welded to the casing and secured to the compression heel, to receive and distribute the thrust of said heel.
4. In a building column having a hollow metal casing filled with a plastic core, and formed with a vertical slot, a beam supporting bracket comprising a web plate with a tension toe at the top projecting into said slot and bearing against the interior of said casing, said plate having an extension depending below said slot to form an extension heel, and a compression plate welded to the casing below the column slot and substantially conforming to the contour of the column casing and defining an arc of at least ninety degrees around the column perimeter, the extension heel of the web plate being rigidly secured to the compression plate so as to effectively distribute all shearing and bearing stresses on the column casing.
